UNITED STATES PATENT OFFICE.

LEONARD H. CRAWFORD, OF INGLEWOOD, WASHINGTON.

SPUR ROLL FOR SHINGLE MACHINES.

Application filed October 16, 1922. Serial No. 534,734.

To all whom it may concern:

Be it known that I, LEONARD H. CRAWFORD, a citizen of the United States, residing at Inglewood, in the county of King and 5 State of Washington, have invented a new and useful Spur Roll for Shingle Machines, of which the following is a specification.

This invention relates to improvements in spur rolls for shingle machines and the primary object of the invention is to provide 10 a spur roll with a plurality of dies having raised numbers, letters or other characters thereon to designate each particular machine and arranged in such manner as to insure 15 the spall or residual segment of the shingle block receiving an impression from said raised characters thus providing a tally by means of which said spalls may be identified with said particular machine and its 20 operator.

The ultimate object of the invention is to provide means which will prevent the waste 25 of material caused by workmen striving to cut a record number of shingles when employed on piece work. Rather than utilize the material to the best advantage of the employer, it is the common practice for shingle machine operators to discard the 30 spalls when they become small and irregular in shape to the extent of retarding their progress. It is needless to state that an operator will refrain from such wasteful practice when he is aware that his mark is being stamped on each spall as evidence of his 35 wastefulness.

With the above and other objects in view which will appear as the description proceeds, the invention consists of the novel construction, adaptation, arrangement and 40 combination of parts hereinafter described and claimed.

These objects are accomplished by devices illustrated in the accompanying drawings, wherein:

45 Figure 1 is a view in longitudinal elevation of a spur roll embodying the features of the invention;

Fig. 2 is a view in transverse vertical section taken on a broken line 2, 2 of Fig. 1;

50 Fig. 3 is a similar view taken on a broken line 3, 3 of Fig. 1;

Fig. 4 is a similar view taken on a broken line 4, 4 of Fig. 1;

55 Fig. 5 is a similar view taken on a broken line 5, 5 of Fig. 1; and

Fig. 6 is a top plan view showing part of

a shingle machine, and showing a spall in its normal operative position therein.

Referring to the drawings throughout in which like reference numerals designate like parts, the numeral 5 designates the cylindrical body portion of a spur roll on which is a plurality of integral wedge shaped spur teeth 6 in spaced apart ring formation.

The numeral 7 designates a plurality of 65 die bases which are preferably formed by integrally combining two of the spur teeth 6. The die proper comprises a number, letter, or other character such as designated at 8 and for the purpose of illustration the number two is used.

It will be noted that the bases 7 and their accompanying dies 8 are spaced around certain rings of teeth in such manner that no two of them are in the same longitudinal 75 alignment. The object of this arrangement is to obviate any tendency which said dies might have in interfering with the grip of said teeth on the shingle block should they be placed in alignment, and also to insure 80 that one or more of said characters will impress itself upon the spall as more fully hereinafter described.

It will likewise be noted that the outer surfaces of the bases 7 are slightly short of 85 the outer points of the teeth 6 in radial length and that the die characters 8 project slightly outside of the outer points of said teeth, as clearly indicated by projected dotted lines in Fig. 2 of the drawings. Although not limiting myself to this particular arrangement, the purpose of same is to insure a substantial contact of said teeth and die characters with the shingle block without interference by said bases.

In Fig. 6 of the drawings I have shown, in part, a top plan view of an upright shingle machine which is the present predominating type of machine in use, and, in which the numeral 9 designates the framework, the 100 numeral 10 designates the circular saw, the numeral 11 indicates part of a shingle block, and the numeral 12 indicates the upper one of the spur rolls shown in dotted lines. As is well understood, in this type of machine 105 there are two spur rolls horizontally arranged, one above the other, and said shingle block is placed between with its grain in an upright position and with the teeth of said spur rolls in engagement respectively with 110 its upper and lower surface ends.

As the shingle block 11 is drawn between

the spur rolls 12 to engage the saw 10 where it is sawed into shingles, the latter part of said block is known as a spall. If said spall happens to be of irregular shape or contains knots or other defects which would necessitate its being shifted in order to utilize all the material to the best advantage, the temptation to cut a record number of shingles leads the operator to knock same out 10 of the machine and begin on a new block rather than relay himself in shifting said spall.

From Figs. 1 to 5 it will be observed that the die characters 7 are arranged in staggered longitudinal relation, the purpose being to place said characters on the roll in such manner that one or more of same will be sure to impress itself upon the spall 11 regardless of its shape. It will be understood that each particular machine and its operator is known by the particular character used on the spur rolls of that machine and that each machine in a mill is designated by a different set of characters. As hereinbefore stated, the operator will discontinue the wasteful practice of throwing away valuable spall material when he is aware that his identification character is stamped thereon and will inevitably be discovered 25 in the spall pile if not before.

While I prefer to show the dies as an integral part of the spur roll, I do not limit myself to this particular construction, it

being obvious that same might be sprung, 35 screwed, or otherwise fastened to said spur roll. It may be remarked that my device is equally applicable to the horizontal type of shingle machine in which the spur rolls are arranged vertically and the shingle block is placed between same with its grain in a horizontal position.

Having thus described my invention, it being understood that such changes may be resorted to as are within the spirit and scope of the invention, what I claim and desire to 45 secure by Letters Patent is:—

1. An article of manufacture comprising a spur roll body portion, spur teeth arranged in spaced apart ring formation on said body portion, dies between said teeth disposed 50 around said body portion, and said dies being positioned in different planes both longitudinal and vertical with respect to the axis of said body portion.

2. An article of manufacture comprising 55 a spur roll body portion, spur teeth arranged in spaced apart ring formation on said body portion, die bases between said teeth, said teeth projecting outside the peripheral line of said bases, die characters on said bases 60 said characters projecting outside the peripheral line of said teeth, and said die bases and characters disposed in longitudinal staggered relation around said spur roll.

LEONARD H. CRAWFORD.
